UNITED STATES PATENT OFFICE.

CHARLES H. MURPHY, OF SCRANTON, PENNSYLVANIA, ASSIGNOR OF
TWO-THIRDS TO DAVID B. HAND AND GEORGE F. GARRITY, OF
SCRANTON, PENNSYLVANIA.

ELECTRIC-RAILWAY SYSTEM.

SPECIFICATION forming part of Letters Patent No. 761,694, dated June 7, 1904.

Application filed September 1, 1903. Serial No. 171,572. (No model.)

To all whom it may concern:

Be it known that I, CHARLES H. MURPHY, a citizen of the United States, residing at Scranton, in the county of Lackawanna and State of Pennsylvania, have invented a new and useful Electric-Railway System, of which the following is a specification.

My present invention relates to a novel electric-railway system of that type characterized by a trolley-line in the form of a third rail from which the current is taken by a trolley or shoe constituting the terminal of a local circuit on a vehicle and including a motor by means of which the vehicle is propelled. Systems of this character have found a wide adoption, because of the inexpensive installation required; but they are open to several serious objections, the most prominent of which is the danger arising from the exposure of the third rail, through which a current of high voltage is constantly passing. To the elimination of the danger mentioned and to the accomplishment of certain other objects, which will more fully appear, my invention consists in forming the trolley-line or third rail in a series of comparatively short insulated sections which are normally dead, but which are arranged to be automatically connected one at a time with an insulated power-line or conductor which, while harmless on account of its insulation, may be still further protected in an underground conduit, if desired.

In the preferred form of the invention illustrated in the accompanying drawings, hereinafter described in detail, and succinctly defined in the appended claims, the several sections of the trolley-line or third rail are arranged to be connected with the power-line or conductor through the medium of a series of electromagnetic switches through which a secondary or subcircuit is automatically closed by a vehicle—as, for instance, a car—as the latter approaches the sections with which the switches are associated.

In said drawings, Figure 1 is a diagrammatic plan view of so much of a double-track railway as is necessary to illustrate the invention. Fig.

2 is a horizontal sectional view of one of the electromagnetic switches, its casing, and connections. Fig. 3 is an end view thereof, and Fig. 4 is a side elevation of the same subject-matter, shown partly in section.

Like characters are employed to designate corresponding parts in the several figures of the drawings.

The go and return tracks 1 and 2 of the railway are composed, as usual, of rails 3 and 4, the latter constituting the return-conductor of the power system. The rails 3 are each composed of insulated sections 5, 6, and 7, the reason for which insulated sectional form will presently appear. Associated with each of the tracks 1 and 2 is a trolley-line in the form of a third rail 8, composed of sections 9, 10, 11, &c., completely insulated from each other. The vehicle 12 (indicated diagrammatically in Fig. 1) is provided with a suitable motor 13, as usual, designed to take current from the third rail 8—as, for instance, through a shoe 14 in sliding contact therewith. The operating-current is not passed through the third rail continuously, as in the ordinary forms of systems now in use, but is supplied to the third-rail sections in succession from a power-line or conductor 15, which is preferably common to both tracks or sides of the railway and is protected in a manner to absolutely preclude the possibility of danger.

The manner in which the power-line is protected is immaterial; but it is preferably provided with an insulating-covering 16 and for greater safety may be located below the level of the ground, either in a conduit or embedded in the earth. In fact, this power-line might, if desired, be elevated out of reach, the essential characteristic of this particular feature of the invention residing in the fact that the power-line is not exposed.

The electrical connection of the third-rail sections with the power-line is effected by means of switches 17, 18, and 19, preferably of electromagnetic form, each switch being constructed substantially in the manner shown in Figs. 2, 3, and 4 of the drawings. Within a casing 20 of any desired form and material

are mounted, preferably adjacent to one end of the casing, a pair of contact-blocks 21, which may be formed at the inner ends of bolts 22, passed through insulating-bushings 23 in 5 the opposite side walls of the casing and secured by nuts 24. Beyond the nuts 24 the bolts 22 are provided with jam-nuts 25, which serve to retain the ends of heavy branch wires 26 and 27. The wire 26 is in electrical connection with a section of the third rail, while the wire 27 is similarly in electrical connection with the line-conductor 15, it being noted that the connections between the wires 26 and 27 and the contacts 21 are protected by housings 28, bolted to the casing 20. The inner ends of the contact-blocks 21 are preferably beveled, as indicated at 29, and are designed to be engaged by a circuit-closing block 30, having its opposite ends correspondingly beveled and carried at the ends of a pair of supporting-rod 31, passed through suitable guides 32 and secured to the armature 33 of an electromagnet 34. The magnet 34 is preferably of the double-coil type, and the armature 33 thereof is provided with a stem 35, slidably received within a spring-barrel 36, bolted at one end to the casing 20 and inclosing a spring 37, bearing against the inner end of the stem 36 and exerting a constant tendency to retract the armature 33, and thus move the block 30 out of engagement with the contact-pieces 21. Obviously the manner of mounting the electromagnet in the casing is not material and need not be described in detail. The action of the spring 37 is augmented by a pair of retracting-springs 38, secured to the opposite side walls of the casing 20 and projecting inwardly into co-operative relation with the opposite ends of the armature 33. 40 When the armature 33 is attracted, these springs act as buffers to prevent violent impact of the moving parts; but when the current passing through the coils of the magnet ceases these springs 38 assist in the retraction of the armature, and thus insure the prompt movement of the circuit-closing block 30. The magnet-terminals 39 and 40 of each switch extend through one end of the casing 20, as shown in Fig. 2, one of these terminals—as, for instance, the terminal 39—being connected to an insulated section of the track-rail 3, and the other terminal—as, for instance, 40—being connected to a feed-wire 41, common to all of the switches embraced 45 by the system. Since the vehicle is not designed to take current from the feed-wire 41 by contact therewith, said wire may be located underground or overhead or disposed of in any desired manner. In Fig. 1 of the drawings the wire 41 is supported by poles *a*, provided with insulating-caps, as usual. This feed-wire is designed to carry a comparatively light current, which need only be sufficient to energize the electromagnets of the 50 switches. A suitable source of electrical en-

ergy—as, for instance, a battery 42—is located at the power plant and is connected up in such a manner that the track-rail 4, which is not of insulated sectional form, will constitute a return-conductor for the secondary 70 or switch-operating circuit. This track-rail 4 is also related to the power-line 15 in a similar manner, so that said track-rail may constitute a common return for the primary or power circuit and also for the secondary or 75 switch-operating circuit.

In describing the system I have addressed myself to one side only of the railway. It will be understood, however, that both sides are identical and that both are supplied with 80 power from the power-line 15 and that the switches of both sides of the railway are energized by current taken from the feed-line 41, either of the track-rails 4 constituting the return-conductor, accordingly as one side or 85 the other of the railroad is considered.

The main generator is indicated diagrammatically at G in Fig. 1, one side thereof being connected to both of the continuous return-rails and the other side having connection with the main power-line. 90

Briefly, the operation of the system is as follows: The several switches being normally open, the third rail is out of electrical connection with the power-line, and as the latter is not exposed a condition of absolute safety obtains. If now a vehicle passes upon the end of one of the insulated track-rail sections—as, for instance, the section 6 of the track-rail 3—this section of the track-rail is electrically 100 connected with the track-rail 4, and a circuit is thus closed through the electromagnet of the switch 18. The magnet being energized, the armature thereof is attracted, the circuit-closing block 30 is moved into engagement 105 with the contact-block 21, and the section 10 of the third rail 8 is thus electrically connected with the power-line or conductor 15. As the contact-shoe 14 of the vehicle is in contact with this third-rail section, the power-circuit is closed through the motor 13 on the vehicle and returns through the track-rail 4. Obviously the advance of the vehicle beyond the track-rail section 6 will effect the opening of 110 that switch-operating circuit which has been closed, and the electrical connection between the third-rail section 10 and the power-line will thus be broken by the opening of the switch 18. 115

It is thought that from the foregoing the construction, operation, and many advantages of my system and the absolute safety thereof will be clearly comprehended by those skilled in the art; but while the present embodiment of the invention appears at this 120 time to be preferable I do not wish to be understood as limiting myself to the structural details defined. On the contrary, I desire to reserve the right to effect such changes, modifications, and variations of the illustrated 125 130

structure as may fall fairly within the scope of the protection prayed.

What I claim is—

1. An electric - railway system including 5 track-rails one of which is continuous and the other composed of insulated sections, a third rail composed of corresponding insulated sections, a continuous non-exposed power-line, electromagnetic switches located between the 10 power-line and each of the third-rail sections, a battery connected to the continuous track-rail, a feed-wire extending along the railway from said battery, wiring connecting the magnet-terminals of each of the switches with the 15 feed-wire and with the insulated track-rail sections, respectively, and a generator having one side connected with the power-line and its opposite side connected to the continuous track-rail.
2. An electric-railway system including a double-track or two-sided railway, each side comprising a continuous track, a sectional track and a corresponding sectional third rail, a power-line common to both sides of the railway, electromagnetic switches interposed between the third-rail sections of each side and the power-line, a feed-wire common to the switches of both sides of the railway, a battery having electrical connection with the 30 continuous tracks and with the feed-wire, wiring connecting one terminal of each switch-magnet with the feed-wire, and wiring connecting the other terminal of said magnet with the sectional tracks of the railway.
3. An electromagnetic switch for railway systems comprising a casing, a magnet therein, an armature provided with a stem, a barrel extending from the bottom of the casing for the reception of the stem, a spring 40 closed within the barrel and bearing against the lower end of the stem, contact-blocks carried by the opposite walls of the casing, and a circuit-closing block supported by the armature and movable into and out of engagement by the contact-blocks.
4. An electromagnetic switch for railway systems including a casing, a magnet therein, an armature for the magnet, a circuit-closing block connected with the armature, contact-blocks provided with shanks extended through the opposite walls of the casing, and means exterior to the casing for retaining said shanks.
5. An electromagnetic switch for railway systems comprising a casing, contact-blocks 50 detachably secured to the opposite side walls thereof and having their proximate ends beveled, a terminally - beveled circuit - closing block, and an electromagnet mounted in the casing and having its armature connected with said block to move the same.
6. An electromagnetic switch for railway systems comprising a casing, contact-blocks

detachably secured to the opposite side walls thereof, a circuit-closing block, an electromagnet mounted in the casing and having its 65 armature connected to said circuit-closing block to move the same, means for attaching wires to the contact-blocks, and housings for said means located exterior to the casing.

7. An electromagnetic switch for railway systems comprising a casing, contact-blocks detachably secured to the opposite side walls thereof and having their approximate ends beveled, a terminally-beveled circuit-closing block, an electromagnet mounted in the casing and having its armature connected with 70 said circuit-closing block, a stem extended from the armature, a spring-barrel guiding the stem, an armature-retracting spring inclosed by the barrel, and means for attaching 75 wires to the contact-blocks.

8. An electromagnetic switch for railway systems comprising a casing, contact-blocks secured to the opposite side walls thereof, a circuit-closing block, an electromagnet mounted in the casing and having its armature connected with 85 said circuit-closing block, combined buffers and armature-retracting springs carried by the casing and disposed to be engaged by the opposite ends of the armature, 90 means for attaching wires to the contact-blocks, and housings for said means.

9. An electromagnetic switch for railway systems including a casing, fixed and movable switch elements therein, an electromagnet 95 whose armature is provided with supporting-rods carrying the movable switch element, guides for said rods, and combined buffers and retracting-springs carried by the casing and disposed to be engaged by the armature.

10. An electromagnetic switch for railway systems comprising a casing, contact-blocks detachably secured to the opposite side walls thereof and having their proximate ends beveled, a terminally - beveled circuit - closing 105 block, an electromagnet mounted in the casing and having its armature connected with said circuit-closing block, a stem extended from the armature, a spring-barrel guiding the stem, an armature-retracting spring inclosed by the barrel, combined buffers and armature - retracting springs carried by the casing and disposed to be engaged by the opposite ends of the armature, means for 110 attaching wires to the contact-blocks, and housings for said means.

In testimony that I claim the foregoing as my own I have hereto affixed my signature in the presence of two witnesses.

CHARLES H. MURPHY.
